UNITED STATES PATENT OFFICE

ROY FIERO GOULD, OF CHICAGO, ILLINOIS, ASSIGNOR TO RESERVE HOLDING COMPANY,
OF KANSAS CITY, MISSOURI, A CORPORATION OF DELAWARE

TELEPHONE SYSTEM

Application filed December 1, 1927. Serial No. 236,937.

The present invention relates to telephone systems, and has to do more particularly with provisions in a private branch exchange, for establishing connections between the subscriber therein, as well as with equipment for taking care of the traffic between a private branch exchange and a main exchange.

The principal object of the invention resides in the provision of improved circuit arrangements and equipment embodying desirable features and advantages in an efficient, simple and economic manner.

One feature has to do with the provision of a line finder switch associated with a connector switch, for interconnecting a calling line with a called line, and means, including a finder distributor switch common to a plurality of line finders, for preventing the actuation of more than one finder switch in response to the initiation of a call at a substation in a private branch exchange.

Another feature of the invention resides in means associated with subscribers' lines in a private branch exchange and cooperating with means in connectors and finder switches for permitting certain subscribers to extend calls to a distant main exchange, and preventing certain other subscribers from enjoying this privilege.

A third feature may be found in an attendant's cabinet in a private branch exchange as disclosed in the present invention, and consists in the unification of certain common relays and other apparatus used by the attendant in the extension of calls, and provision of such apparatus within the attendant's cabinet in order to render an efficient and simple unit.

A further feature resides in various relays and other apparatus individual to a trunk from a main exchange to a private exchange, and in combining such equipment with a connector switch accessible to the trunk.

Other features relate to novel provisions and methods for transmitting impulses from an attendant's cabinet to switches in the private branch exchange and to switches in the main exchange in order to extend calls, and to novel provisions and methods for trans-

mitting ringing current to called stations in the private branch exchange.

The novel features through the provision of which the above mentioned and other desirable results are obtained will be described in connection with the accompanying three sheets of drawings, in which—

Fig. 1 illustrates subscribers' substations in a private branch exchange, as well as a finder switch and connector switch for establishing a connection between the stations, and the provision of a finder distributor switch for controlling the actuation of the finder switches;

Fig. 2 shows a trunk line extending from a main exchange and terminating in an attendant's cabinet in a private branch exchange. This figure also shows various keys and other equipment associated with the attendant cabinet, and a group of relays which may be considered common to a plurality of trunk lines; and

Fig. 3 shows an incoming connector switch located in the private branch exchange and associated with the trunk line extending from the main exchange to the attendant's cabinet. Various relays, and other apparatus, which are individual to a trunk line have been combined with the connector shown in this figure.

Referring now particularly to Fig. 1, at the left there is illustrated a calling substation in the private branch exchange. This substation includes the usual talking and signalling equipment consisting of the transmitter 1, the receiver 2, the switch hook 3, the calling device 4, the ringer 5, and the condenser 6, which, together with the ringer is bridged across the line conductors 7 and 8. The line conductors terminate at the exchange in a line equipment comprising the relays 10 and 15.

The line finder F is associated with a connector C, and its actuation is controlled by a finder distributor switch FD shown in the lower part of the drawing. The connector comprises a number of relays and other equipment which will be described in connection with its operation, and has access to subscribers' lines, such as the line B shown at

55

the right of the drawings, and it has also access to the attendant's cabinet and to the trunk line extending to the main exchange.

Having described in general the apparatus illustrated in Fig. 1, the operation of this equipment in establishing a connection between the calling subscriber A and the called subscriber B shall now be described in detail.

Each line terminates in a line and cut off relay 10 and 15, respectively, which cause the preselected finder, such as F, to find the line when the receiver is removed at the substation in order to extend a call. When the line is found, the finder extends the line through to the associated connector switch C and the distributor switch FD is caused to operate and to preselect another free finder switch.

When the receiver at the substation A is removed, relay 10 is energized over its upper winding in series with the calling line, its circuit extending from battery, upper winding of relay 10, armature 16 and its resting contact, line conductor 7, loop of the substation A, line conductor 8, resting contact and armature 18, to ground. Relay 10 operates and removes at its armature 11 ground from a contact in the finder switch bank accessible to wiper 23 of the finder switch, in order to permit the preselected finder to find the calling line. At its armature 12, the relay 10 closes a circuit for the relay 41 of the finder distributor, from ground, resting contact and armature 17, make contact and armature 12, resting contact and armature 37, and winding of relay 41 to battery.

Assuming that the wipers of finder switch F which was preselected by the finder distributor FD in a manner which shall be described subsequently, are in engagement with the contacts of the calling line A, relay 41 of the finder distributor, upon operating, causes the connector switch C associated with the finder F to connect its line relay 57 across the calling line. This operation will be described presently. It shall be assumed first that the finder is not resting in engagement with the calling line, and, accordingly the operation of the finder switch F in connection with seeking the calling line will be described next.

Upon operating, the relay 41 in the finder distributor FD closes a circuit for the motor magnet 25 of the finder, from battery, winding of the motor magnet 25, interrupter contact 26, contact in the bank of the distributor accessible to wiper 32, armature 42 and its make contact, wiper 33, resting contact and armature 54, wiper 23 of the finder switch, armature 11 and its resting contact to ground. In order to understand this circuit, it must be remembered that the finder in question is not in engagement with the calling line, but with a line which is assumed to be in the condition of rest as shown in the drawing, that is, with its line relay 10 in normal position. Accordingly, the wiper 23 of the finder

switch which is supposed to hunt for the calling line encounters ground over the armature 11 of the line relay 10. Relay 41, upon operating, also attracts its armature 43 and connects thereby ground to the winding of relay 39. This relay, however, is prevented from operating at this moment on account of being short circuited to ground over wiper 23 of the finder switch and armature 42 of relay 41. As long as the finder switch F is seeking the calling line, its wiper 23 will encounter ground, and relay 39 in the finder distributor switch will be prevented from energizing. The motor magnet 25 of the finder switch operates, interrupting its own circuit at interrupter contact 26, restores, and advances the wipers 21 to 24, inclusive, over the associated bank contacts. The foregoing operation continues until the calling line is found.

When the calling line is found, wiper 23 will not encounter ground since armature 11 of line relay 10 is in operated position, and the motor magnet 25 will cease to operate. The short circuit around the winding of relay 39 is removed at the present moment, and this relay energizes in series with the motor magnet of the finder switch from ground at armature 43. The motor magnet 25 does not operate in series with relay 39 on account of the high resistance of this relay. Relay 39 operates its armature 40, thereby closing a circuit for energizing relay 36. At its armature 40' relay 39 closes a circuit for the lower winding of relay 50 of the connector switch C. The latter circuit, it will be seen, extends over wiper 31 of the distributor. The function of relay 36 of the distributor will be explained presently. However, it should be noted at this time that relay 36 opens at its armature 37 the circuit for the slow acting relay 41, in order to prevent other calls from being extended through to a connector until the distributor has selected another finder.

Relay 50, upon operating, attracts its armature 55, and removes thereby ground from a contact in the distributor bank accessible to wiper 34. Every connector keeps a multiple ground connected to this contact, accessible to wiper 34, by means of armatures 55 of the various relays 50. The purpose of this multiple ground is to stop a distributor in case all finders should be found busy. The overflow register 45 will be operated in such a case in order to indicate the condition. Detailed description of this operation will be presented later on.

At its armature 54 the relay 50 opens the connection of the wiper 23 of the finder switch with a bank contact of the distributor switch and connects ground to the wiper 23 in order to energize the cut-off relay 15 in series with the lower winding of the line relay 10, by way of armature 11 of the line re-

lay 10. This ground also extends to the private normal conductor 9, which appears, together with the line conductors 7' 8' in bank contacts such as 105, 106 and 107 in the various connector switches. The grounding of the private normal conductor 9 serves the purpose of busying this line against seizure from a connector.

At armature 52 a circuit is prepared which is of importance in connection with discriminating service in which a certain subscriber is prevented from calling out into the main exchange. The connector C has access to trunk lines terminating in the main exchange, over a certain level, and when the connector is operated to this level the contact springs 110, 111 and 112 will be operated, and the wiper 22 of the finder switch will be extended by way of the armature 52 to the private wiper 103 of the connector switch. If a line, which is not permitted to call to the main exchange, attempts such a call, ground will be extended over the discriminating conductor 13 and the wiper 22 of the finder switch 25 to the private wiper 103, which produces conditions with respect to the circuits of the connector, present only in case all the trunk lines accessible to the connector in that level should be busy. Accordingly, the connector will rotate automatically and the subscriber who is not entitled to call to the main exchange will receive a busy signal. This operation will be described presently in detail.

At armatures 51 and 56, the relay 50 extends the line circuit of the calling station to the line relay 57 of the connector switch.

Relay 15 of the line circuit was operated over a circuit including the armature 54 relay 50. At armature 16 this relay opens the circuit over the upper winding of line relay 10; at armature 17 ground is removed from the circuit over which relay 41 was originally energized; and at armature 18 ground is removed from the line conductor 8. Line relay 10 remains energized in series with the cut off relay 15 to ground over the attracted armature 54 of relay 50. The calling line is thus cleared of attachments and connected through to the line relay 57 of the connector, which circuit can be traced from battery, upper winding of relay 57, resting contact and armature 78, armature 51 and its make contact, wiper 21 of the finder switch line conductor 7, loop of the calling substation A, line conductor 8, wiper 24 of the finder switch, make contact and armature 56, armature 81 and its resting contact, lower winding of the line relay 57, contact spring 116 of the off-normal contacts and conductor 116', which terminates in a tone source for conveying to the calling subscriber that he may operate his calling device in order to transmit impulses to the connector.

Line relay 57 operates its armature 58, completing thereby a circuit for the slow act-

ing release relay 59. The latter relay actuates armature 60 connecting ground to the holding conductor 60' to which is connected the holding winding of relay 50 over the armature 53. This prevents the relay from deenergizing when its original circuit including its lower winding is opened by the finder distributor preselecting another finder switch.

At armature 61, the relay 59 opens a point in the circuit of the release magnet 108 and closes a point in the impulsing circuit; and at armature 62 ground is connected to a contact in the bank of the finder distributor in order to mark the associated finder busy.

The operations of the finder distributor in preselecting an idle finder switch will be described next.

It will be remembered that relay 39 was energized to close a circuit for relay 36 at its armature 40. Relay 36 operates its armature 38 and connects thereby the circuit of the motor magnet 35 of the distributor switch from battery, winding of the motor magnet 35, make contact and armature 44, armature 38 and its make contact, make contact and armature 40 to ground. At armature 37 the relay 36 interrupts the circuit of the slow acting relay 41. This relay, however, does not fall back immediately on account of being slow acting, and, therefore, the circuit for the motor magnet is initially established over attracted armature 44. When relay 41 deenergizes it opens the circuit of the motor magnet 35, which deenergizes and advances the wipers 31 to 34, inclusive, by one step.

The relay 41 also opens the circuit of relay 39 at its armature 43. In case the wipers are now in engagement with an idle finder switch, relay 39, upon deenergizing, removes ground from the distributor wiper 31, and opens at its armature 40 the circuit of motor magnet 35 and of relay 36. Therefore, the wipers of the distributor come to rest and an idle finder switch is thus preselected and prepared to be actuated to hunt for a line in case a subscriber to which the finder switch has access should initiate a call.

Assuming, however, that the distributor switch has advanced its wiper into engagement with a busy finder switch, the wiper 34 will encounter ground over an armature 62 of an operated relay 59 of a connector which is associated with that busy finder switch, and a circuit will be closed for maintaining the relay 36 of the distributor in operated position. The ground encountered by wiper 34 of the distributor is also transmitted by way of armature 38 to the motor magnet 35, which operates again, opening its interrupter springs 35' and thereby interrupting its own circuit for advancing its wipers into engagement with another set of bank contacts associated with another finder switch. This operation continues until the wiper 34 finds an idle finder switch, that is, a contact which

is not grounded by an armature such as 62 of a relay 59.

In case all finder switches accessible to the distributor FD are busy, the wiper 34 will

5 encounter ground over the winding 45 of an overflow register connected to the last bank contact. This bank contact is also connected in multiple to armatures such as 55 of relays 50, which, as long as a connector is 10 idle, keep ground connected to this bank contact. When the last connector and with it the associated finder switch, is taken into use, the corresponding relay 50 removes ground at its armature 55 from the multiple contact.

15 Therefore, when the wiper 34 reaches this bank contact, a circuit will be closed from ground, winding of the overflow register 45, bank contact accessible to wiper 34, winding of relay 36, to battery. Relay 36 does not energize in series with the windings of the overflow register 45 while the register operates to indicate the condition "all finders busy". Relay 36, being prevented from energizing, releases its armature 38, opening thereby the circuit

20 of the motor magnet 35. The automatic rotation of the finder distributor is now prevented and the distributor stops until a finder becomes idle, that is, until an armature such as 55 connects a multiple ground to the contact 25 with which the wiper 34 is in engagement. When this occurs, relay 36 again operates, closing its armature 38 and causing the finder distributor to hunt for the idle finder switch. The overflow register 45, being short circuited by ground at armature 55 of relay 50,

30 associated with the connector which has become idle, releases, while the finder distributor rotates its wipers to seek the idle finder. Relay 36 will remain energized and thus keep the circuit of the motor magnet 35 closed as long as wiper 34 encounters contacts associated with busy connectors, which contacts are grounded at armatures such as 62. However,

35 when an idle finder is found, the wiper 34 will not encounter ground since the idle finder is one which is associated with an idle connector,

40 in which the relay 59 is in deenergized position and keeps the armature 62 open, and relay 36 will, accordingly, deenergize and open

45 the circuit of the motor magnet 35. Thus, the finder distributor comes to rest when an idle finder switch is found which can be used for extending another call.

50 It shall be assumed next that the subscriber at the calling station replaces his receiver at its stage of the extension. When this occurs,

55 the circuit for the line relay 57 in the connector is opened. The line relay restores and opens the circuits to relay 59. Upon deenergizing,

60 relay 59 removes ground from the bank contact accessible to wiper 34 of the distributor switch to make the associated finder switch free and opens the circuit of the locking winding of relay 50. Relay 50 restores and dis-

65 connects the connector from the line; removes ground from wiper 23 of the finder switch, thereby releasing the cut-off relay 15 and the line relay 10 and also removing the ground from the private normal conductor 9; places a multiple ground on the contacts accessible to wiper 34 of the distributor switch; and opens its armature 52, thereby interrupting the prepared circuit for discriminating service. Line relay 10 grounds the corresponding contact in a finder switch bank accessible to wiper 23 so that a finder seeking another calling line will not stop on these bank contacts.

70 The description of the operation of the connector switch in extending calls to the wanted station B will now be continued.

75 It will be remembered that the line relay 57 was energized over the loop of the calling station A and that the subscriber received a dial tone over the conductor 116' which indicated to him that he may operate his calling device in accordance with the digits of the desired subscriber's number.

80 When the subscriber operates his calling device, the line relay 57 will be interrupted a number of times in quick succession in accordance with the digit from which the dial was operated. At its armature 58, the line relay closes; at each interruption, a circuit for the slow series relay 63 and the vertical magnet 67. This circuit may be traced from ground, armature 58 and its resting contact, armature 61 and its make contact off normal springs 118, winding of relay 63, winding of the vertical magnet 67, battery. The wipers 102, 103, and 104 of the connector are raised by one step, and the various off-normal contacts are thrown into their alternate positions. The circuit for the lower winding of the line relay, which originally extends over

85 springs 116 of the off normal contact, is opened, and a new circuit is closed including the off normal contacts 117. This disconnects the dial tone conductor 116'. Springs 118 over which the rotary magnet 67 received the first impulse is also opened while springs 118' are closed. Since relay 63 is operated at this time the armature 65 is in attracted position and a new circuit is provided for the vertical magnet 67 including the off normal springs 118' and the armature 65 and its make contact. Due to their slow release characteristics, the relays 59 and 63 remain

90 operated during impulsing.

95 After the last impulse of the series, the relay 63 restores and transfers the impulsive circuit from the vertical magnet 67 to the rotary magnet 100.

100 When the calling subscriber operates his calling device for the second digit the line relay 57 will be interrupted again a number of times in accordance with the digit dialled, and at its back contact and armature 58 it will close the circuit for the slow release relay 68 in series with the rotary mag-

105

110

115

120

125

130

net 100. This circuit may be traced from armature 65 and its resting contact, resting contact controlled by armature 74, winding of relay 68, resting contacts and armature 98, winding of the rotary magnet 100, to battery. Relay 68 operates and at its armature 69 opens the circuit to the lower starting winding of switching relay 92 in order to prevent a premature operation of the switching relay as the private wiper 103 passes over idle lines. At its armature 70 the relay 68 short circuits the normally closed contacts controlled by armature 74, through which the impulse circuit is taken, so that this circuit will not be opened when the relay 72 operates as the private wiper 103 passes over busy lines. The rotary magnet 100 rotates the shaft and with it the wipers 102, 103, and 104, advancing them to the contacts of the desired line. Due to its slow-to-release characteristics, the relay 68 remains operated during impulsion.

It will be assumed first that the line to which the wipers have been advanced is busy. The private contact, such as 106, of a busy line is connected to ground. When the private wiper 103 encounters the busy contact a circuit will be closed for the relay 72 which includes armature 69 and its make contact, interrupter springs 101 controlled by the rotary magnet, winding of relay 72 to battery. Relay 72 operates its armature 73, connecting thereby ground from the holding conductor 60' to the conductor 101' in order to insure its operation after the relay 68 de-energizes, which happens shortly after the transmission of impulses ceases. At its armature 74, the relay 72 opens the original energizing circuits of relay 68; and at its armature 75 a circuit is closed for the transmission of the busy tone to the calling subscriber, which circuit includes the armatures 66, 71 and 75, and which will be completed upon the deenergization of relay 68 and retraction of armature 71. Relay 72 at its armature 73 disconnects the lower winding of the switching relay 92 in order to prevent an energization of this relay in case the busy line should become idle.

When the calling subscriber hears the busy tone transmitted over the conductor 66' over a circuit intimated above, he replaces the receiver, opening thereby the circuit for the line relay 57. The line relay restores and opens the circuit of the slow release relay 59. This relay removes ground from the holding conductor 60' which causes the deenergization of the relays 50 and relay 72. At its armature 61 and its resting contact the circuit is closed for release magnet 108 from ground over armature 58 and its resting contact, spring 61 and its resting contact, off-normal springs 115, and winding of the release magnet 108 to battery.

In case the called line is free from the

switching relay 92 will operate over a circuit from ground on the holding conductor 60', armature 73, and its resting contact, lower winding of the switching relay 92, resting contact and armature 69, private wiper 103, contact 106 of the idle line, and to battery over the cut-off relay such as 15 in series with the lower winding of a line relay such as 10 of the called line. The switching relay 92, at its armature 95 connects the grounded holding conductor 60' directly to the private wiper 103 for marking the called line busy to other connectors. At armature 96, the switching relay connects itself in a holding circuit involving its upper winding and the holding conductor 60'; at armature 98 it disconnects the rotary magnet 100; at armature 94 it prepares the ring-back circuit; and at armatures 93 and 99 it closes the ringing circuit which extends from ground, resting contact and armature 91, armature 99 and its make contact, wiper 104, bank contact 107, condenser and ringer in series with the switchhook of the called station, bank contact 105, wiper 102, make contact and armature 93, armature 87 and its resting contact, lower winding of the ring-cut off relay 86, to battery at an alternating current source. In the present case ringing current is superimposed upon battery and connected to the lower winding of relay 86 over conductor 86'.

A fraction of the generator current traverses a circuit over the condenser 88 and the telephone at the calling station to give the calling party the ring-back tone.

When the receiver is removed at the called substation, the ringer and the condenser which are normally bridged across the line conductors are removed, and a direct loop circuit is provided over which the ring-cut off relay 86 operates. At its armature 89 this relay closes a holding circuit for itself over its upper winding to the grounded holding conductor 60'; at its armatures 87 and 91 it switches the line through and cuts off the ringing current; and at its armature 90, the relay 86 closes a circuit for the lower winding of the back bridge impedance 76 for transmitting talking current to the called line. This circuit extends from ground, make contact and armature 97, armature 90 and its make contact, lower winding of impedance 76, armature 80 and its resting contact, make contact and armature 91, armature 99 and its make contact, wiper 104, bank contact 107, loop of the called substation, bank contact 105, wiper 102, make contact and armature 93, armature 87 and its make contact, resting contact and armature 79, and upper winding of the impedance 76 to battery. The calling station receives talking current by way of the windings of line relay 57.

The subscribers replace their receivers at the end of the conversation. When the receiver at the calling station is replaced, the

circuit to the line relay 57 is open. This relay restores and opens the circuit of relay 59. When relay 59 restores, it removes ground from the holding conductor 60' at its armature 60, thereby opening the holding circuits of relays 50, 86, and 92. At armature 62 the relay 59 removes ground from a contact in the bank of the distributor which is accessible to wiper 34. At its armature 61 it closes the circuit to the release magnet 108 which has been traced previously. The release magnet operates, allows the shaft to return to normal and to restore the off normal springs, which open the circuit of the release magnet.

The entire equipment is now in position of rest and ready to serve for the extension of another call.

The operation of the equipment in connection with outgoing service to the main exchange will be described next. By outgoing service is meant the extension of a call from a private branch exchange station, such as station A, to a distant main exchange. Trunk lines terminating in a distant main exchange are accessible to the connector C over a certain level, in the present case over the ninth level. The switch is arranged to give outgoing service only to those lines whose associated line and cut-off relay circuit does not ground the discriminating trunk 13 which is accessible to wiper 22 of the finder switch. Therefore, lines which shall receive outgoing service will not be provided with a discriminating conductor such as 13. The contacts which are operated by the spring 14 shown at the left of relay 50, will be operated when the shaft of the connector switch is raised to the ninth level, and the contacts which are operated by spring 14' will be operated when the switch shaft is raised to the ninth or to the tenth level. The physical arrangement by which contact springs such as 14 and 14' are actuated is disclosed in the application of Hans Sengebusch, Serial Number 54,597, filed September 5, 1925.

When a subscriber operates the connector C to the ninth level, provided he is entitled to outgoing service, the connector will rotate automatically and hunt for an idle trunk line terminating in a distant exchange. However, when a subscriber who is not entitled to outgoing service actuates the connector to the ninth level, the connector will rotate its wiper past the last available trunk, due to the discriminating conductor 13 being grounded, and the subscriber will receive a busy tone.

The operations intimated above, will now be explained in detail.

When the subscriber at the calling station operates his calling device, the line relay 57 will deenergize in accordance with the dialled digit, as was described previously, and will transmit impulses to the vertical magnet by

way of the series relay 63. The release relay 59 was, of course, operated immediately upon the first energization of line relay 57. The vertical magnet 67 raises the wipers of the connector opposite the ninth level. When the ninth level is reached, both sections of the normal post springs 14 and 14' operate and connect the discriminating trunk 13 through to the private wiper 103 by way of the armature 52 of relay 50, contact spring 110, and wiper 22 of the finder switch.

It shall be assumed first that the calling subscriber is not entitled to outgoing service. Accordingly, the connector must rotate in the ninth level without engaging with any of the outgoing trunks leading to the distant main exchange, and busy tone must be transmitted to the calling subscriber. This is done as follows:

Since it is assumed that the calling subscriber is not entitled to outgoing service, the discriminating trunk 13 is provided, that is, ground is transmitted over the wiper 22 of the finder switch, and over a path which was traced previously, to the private wiper 103. This ground on the wiper 103 actuates the connector as if all trunks encountered in the ninth level were busy, i. e., the connector rotates the wipers off the bank and transmits busy tone to the calling line.

Relay 63 restores when the calling subscriber has finished dialling. Relay 72, prior to the deenergization of relay 63 is operated from ground on springs 112, springs 120 and 119 of an off-normal contact which is adapted to operate on the eleventh rotary step of the ninth and tenth level, armature 64 and its make contact, conductor 101', interrupter spring 101, and winding of relay 72 to battery. At armature 74 the relay 72 prepares the circuit for the rotary magnet 100, which is effective upon the deenergization of relay 63, from ground on springs 112, springs 120 and 119, armature 64 and its resting contact, armature 74 and its make contact, winding of relay 68, resting contact and armature 98, winding of the rotary magnet 100 to battery. The rotary magnet operates and opens its interrupter springs 101, thereby interrupting the circuit of relay 72. This relay in turn interrupts at its armature 74 the circuit for the rotary magnet 100. When the rotary magnet deenergizes it closes its interrupter springs 101 thereby again closing the circuit for relay 72 by way of the armature 69 of relay 68 which is slow acting and is therefore in operated position. The ground for the reoperation of relay 72 is in this case derived from the discriminating trunk 13 by way of the wiper 22 of the finder switch, normal post springs 110 and the armature 52. Upon the operation of 72 it closes the circuit for the rotary magnet again at its armature 74. The rotary magnet accordingly energizes, opening at its interrupter contacts 101 the

circuits for relay 72. This interaction of the rotary magnet and the relay 72 continues until the wipers 102, 103 and 104 rotate past the eleventh contacts in the ninth level. At this time the spring 120 is operated, connecting the ground from spring 112 to the conductor 101'. In the condition in which the contact 120 is shown, the circuit was closed for the rotary magnet. Therefore, when the 5 springs 119 and 120 separate, the circuit for the rotary magnet is interrupted, and further rotation of the shaft is impossible. Relay 72, however, remains energized over the interrupter spring 101 and the contacts 121 and 120 which close when the wipers advance to the eleventh rotary step in the ninth level. Relay 68 releases after a while, and closes at its armature 71 the circuit for the 10 transmission of the busy tone from the conductor 66' by way of the armatures 66, 70 and 75.

When the subscriber replaces his receiver in response to recognizing the busy tone, the switch is released in a manner which has already been described in a previous paragraph.

It will next be assumed that the subscriber who operates the connector to the ninth level is entitled to outgoing service. In this 20 case the wiper 22 of the finder switch does not transmit ground to the private wiper 103 as in the previous case since the discriminating conductor 13 is missing. The connector will therefore rotate in the ninth level 25 until it encounters an idle trunk leading to a main exchange. This is accomplished in the following manner:

Relay 63 is operated during the vertical operation of the switch and has its armature 40 64 in operated position. Therefore, when the ninth level is reached, ground is transmitted for the operation of relay 72 from the spring 112 of the normal post contact, by way of springs 120 and 119, armature 64 and its make contact, conductor 101' interrupter contact 101, winding 72, to battery. Relay 72 again attracts armature 74, thereby preparing a circuit for the operation of the rotary magnet 100, which will be effective 45 exactly as in the previous case upon the de-energization of relay 63, shortly after the impulse transmission for the vertical magnet 67 terminates. The rotary magnet 100 receives therefore an impulse immediately 50 upon the restoration of relay 63 and opens the circuit of the relay 72 at its spring 101. The wipers of the connector are now in engagement with the first trunk leading to the main exchange. If this trunk is idle, 55 the connector must stop and complete the connection from calling subscriber to the idle trunk. If the trunk is busy, however, the connector must take another rotary step and advance the wiper into engagement with the 60 next trunk.

It shall be assumed that the first trunk encountered by the connector is busy. If this is the case, the private wiper 103 finds ground.

Shortly after the rotary magnet 100 has taken its step, its circuit is opened at armature 74 of relay 72 which in turn was interrupted at interrupter spring 101. Therefore, relay 68 deenergizes. However, being slow acting, it retains its armatures for a 70 while after the circuit is opened, and at armature 69 a circuit is closed for energizing the relay 72, which may be traced from ground encountered by wiper 103, armature 69 and its make contact, conductor 101', interrupter spring 101, and winding of relay 72 to battery. Relay 72 therefore energizes and closes at its armature 74 the previously 75 traced circuit for the rotary magnet 100 which involves the relay 68. The rotary magnet takes another step, advancing its wipers to the next set of bank contacts associated with another trunk line. Upon energizing, the rotary magnet opens its interrupter springs 101, thereby opening the circuit for relay 72, and this relay, in de-energizing, opens at the armature 74 the circuit for the rotary magnet 100.

In case the second trunk is found busy, relay 72 will again operate, and will close the circuit for the rotary magnet, which will take another step in precisely the same manner as was already described.

When an idle trunk is encountered by the wiper 103 no ground will be found, and, accordingly, a reenergization of the relay 72 is impossible. The rotary magnet 100 will therefore not take another step and will keep the wipers 102 to 104, inclusive, in engagement with the idle trunk line. The switching relay 92 will be operated from ground on the holding conductor 60', armature 73 and its resting contact, lower winding of the switching relay 92, resting contact and armature 69, private power 103, bank contact associated with the release trunk of the idle trunk line leading to the main exchange, and battery over a relay at the main exchange.

At its armature 96, the relay 92 provides a locking circuit for itself involving its upper winding to ground at the holding conductor 60'; at armature 98, the circuit for the rotary magnet is opened, at armature 95, the private wiper 103 is grounded directly over the holding conductor 60' in order to make the trunk busy to other hunting connectors; and, due to the attraction of armature 95, the winding of relay 77 is connected in series with the lower winding of the relay 86 by way of the spring 111 of the normal post spring 14. The winding of relay 77 is connected to the holding conductor 60' and encounters battery over the conductor 86', in series with the lower winding of relay 86. Upon operating, relay 77 attracts arma- 115 120 125 130

tures 79 and 80, thereby removing the impedance 76 from across the trunk conductors. At its armature 78 and 81 the relay 77 removes the line relay 57 from the line circuits. Relay 86 also operates in circuit with relay 77 and locks itself over its upper winding and its armature 89 to the holding conductor 60'.
 5

The connection extends now directly to the trunk conductors and may be traced as follows:
 10

Wiper 102 which is in engagement with a bank contact associated with a trunk conductor, make contact and armature 93, winding of relay 84, make contact and armature 78, armature 51 and its make contact, wiper 21 of the finder switch, line conductor 7, loop of the calling line, line conductor 8, wiper 24 of the finder switch, make contact and armature 56, armature 81 and its make contact, make contact and armature 91, armature 99 and its make contact, wiper 104 which is in engagement with a bank contact associated with the other trunk conductor.
 15

Therefore, the loop of the calling substation extends in a clear metallic circuit to the main exchange over the trunk seized by the connector. Relay 84 is energized in the circuit and has operated its armature 85 which provides a holding circuit for the release relay 59. This is necessary since the release relay must remain operated, and since its original circuit has been opened at armature 58 of the deenergized line relay 57. Due to a slow release characteristic, relay 59 remains operated in the interval between the restoration of relay 57 and the operation of relay 54.
 20

The succeeding series of impulses from the calling substation cause the switches in the central office to complete the desired connection in the usual manner.
 25

The release of the connection takes place when the calling subscriber replaces his receiver. The circuit for relay 84 is thereby opened, and this relay deenergizes retracting its armature 85, which interrupts the circuit for the slow release relay 59. Relay 59 releases, and, upon retracting its armature 60 it opens the holding circuit for relays 50, 77, 86, and 92; at armature 62 it removes ground from a bank contact of the finder distributor in order to mark the finder switch F idle; at armature 61 the circuit is closed for the release magnet 108 from ground, armature 58 and its resting contact, armature 61 and its resting contact, off-normal contacts 115, and windings of release magnet 108 to battery. When the shaft of the connector switch is restored to normal, the off-normal springs 115 are open and the circuit for the release magnet 108 is thereby interrupted.
 30

In case all the trunks accessible to the connector switch are busy, the shaft, at the eleventh rotary step, operates the cam springs 119, 120 and 121. The rotary magnet upon

restoring, closes the circuit to relay 72 over the cam springs 121 and 120. Relay 72 at its armature 74 connects the rotary magnet again to the circuit, which, however, is incomplete on account of the cam springs 120 and 119 being separated. A further rotation is therefore inhibited. At its armature 75, the relay 72 closes the circuit for transmitting to the calling party the busy tone. This operation, as well as the operations for releasing the switch when the subscriber replaces his receiver in response to the busy tone have been described in detail previously.
 35

The tenth level of the connector is reserved for extending calls to the attendant in the private branch exchange, that is, the connector has access over the tenth level to trunks terminating in the attendant's cabinet. The operations of the equipment in connection with service to the attendant do not materially differ from the operations already explained. The service will therefore be described only briefly and circuits will be traced only where it is necessary for the sake of easy understanding.
 40

When the calling party operates the calling device in accordance with the digit designating the tenth level, the line relay 57 will follow the impulses, and, at the back contact of armature 58, will close the circuit to relay 63 in series with the vertical magnet 67. The vertical magnet raises the shaft, moving the wipers to the tenth level.
 45

The normal post spring designated 14' operates on the ninth step of the shaft and closes the circuit to relay 72 through the make contact and armature 64 of relay 63. Accordingly, relay 72 operates.
 50

At the termination of the impulse series, relay 63 restores and closes the circuits to relay 68 and the rotary magnet 100. The rotary magnet rotates the shaft, advancing the wipers to the first trunk, and opens the circuit to relay 72. This relay restores and opens the circuits to relay 68 and to the rotary magnet.
 55

In case the first trunk encountered is idle, the connector switch seizes the trunk as explained previously in connection with the service to the distant main exchange.
 60

In case the first trunk should be busy, the rotary magnet on restoring, closes the circuit to relay 72 from ground on the private wiper 103. Relay 72 operates; closes its locking circuit; and closes the circuit to relay 68 and to the rotary magnet. The rotary magnet, accordingly, rotates the shaft, advancing the wiper to the next trunk and opens the circuit to relay 72, which restores and opens the circuit to the rotary magnet. The foregoing operations continue until an idle trunk is found or until the wipers pass off the bank in the tenth level.
 65

When an idle trunk is found, removal of

ground from the private wiper 103 prevents further closing of the circuit to relay 72. Relay 68 restores and closes the circuit to the lower winding of relay 92 in series with a relay in the attendant cabinet. The switching relay 92 operates; closes the circuit to its locking winding; opens a part of the incomplete circuit to relay 68 and to the rotary magnet 100, replaces the indirect ground on the private wiper with direct ground; and connects generator current to the calling line through the condenser 88 to give the calling party the ring back tone.

When the attendant answers, a loop circuit is provided for the operation of relay 86 over its lower winding. Upon operating relay 86 closes the circuit to its upper locking winding at its armature 89; removes the ring back tone from the calling line and connects battery to the trunk through the impedance 76.

The attendant in the private branch exchange completes the desired connection, and conversation can take place, talking current being supplied to the calling station over the windings of relay 57.

Upon the termination of the call, the calling subscriber replaces his receiver and opens thereby the circuits to the line relay 57. The line relay restores and opens the circuit to relay 59. Upon restoring, relay 59 removes the ground from the distributor bank contact accessible to wiper 34; opens the locking circuit to relays 92, 86, and 50; and closes the circuit to the release magnet 108, to cause the connector to release in a manner already described.

In case all trunks accessible to the tenth level of the connector should be busy, the shaft, on the eleventh rotary step, operates the cam springs 120. The rotary magnet on restoring, closes the circuit to relay 72 from ground through the cam spring 121 and 120. The operation of the switch from this point on is as explained in connection with the hunting for an idle trunk leading to a distant main exchange.

The operation of the equipment in the attendant's cabinet will now be explained with reference to Figs. 2 and 3. However, before opening the discussion of the equipment shown in these figures, a few outstanding features will be recalled which have been mentioned briefly in another paragraph.

Fig. 2 shows a trunk line comprising the trunk conductors 200, 201, which trunk line connects the private branch exchange with a main exchange, and terminates in the private branch exchange in the attendant's cabinet as shown in Fig. 2. Connections are branched off from the trunk line to equipment in the attendant's cabinet in order to provide means for certain operations involving the attendant, and the trunk line, as shown in this fig-

ure terminates normally in an incoming connector switch shown in Fig. 3.

The outstanding feature in connection with the attendant's cabinet consists in the unification and combination of various relays which are common to a plurality of trunk lines. These relays are shown in the lower part of Fig. 2.

The trunk line 200-201 is a two-way trunk line and is, accordingly, accessible to local connectors in the private branch exchange over the conductors 202, 203, and 204 which terminate in bank contacts in certain levels of the connectors such as the one shown in Fig. 1.

The conductors 205, 206 and 207 are provided for night service. These conductors terminate in the line equipment of a predetermined substation, and, by throwing the key 208, the attendant connects the incoming trunk from the main exchange directly to this substation. A call, coming in from the main exchange, will, in operated position of the key 208, always terminate at this substation.

The trunk, at its distant end in the main exchange is provided with a lineswitch for extending a call from the private branch exchange by way of selectors to a desired party in the main exchange. Normally, there is ground and battery potential on the trunk conductors 200 and 201 from the equipment of the lineswitch at the distant end of the trunk line. However, should the trunk be seized in the main exchange by a subscriber desiring to extend a connection to the private branch exchange, the battery and ground potential on the trunk conductors 200 and 201 will be reversed for a purpose which will be explained later on.

Various keys are provided at the attendant's position, the purpose of which will be described as the description progresses. There is also shown an operator's telephone at 245, and a calling device 246. By means of the calling device 246 the operator is enabled to extend connections either to a subscriber at the private branch exchange, or, over the trunk line, to a subscriber in the main exchange.

The relays 287 and 289 are impulsing relays. These relays, in cooperating with the relay 283, enable the operator to transmit impulses to switches in the private branch exchange in order to extend a connection to a desired party. However, if the attendant desires to extend a connection over the trunk line to the main exchange, her calling device 246 will be connected in a direct loop circuit across the trunk conductors 200 and 201 in a manner that will be explained subsequently.

In addition to the equipment intimated above, trunk lines, such as the trunk lines 250 and 266, terminate at the attendant's position in keys 248 and 264. These trunk lines are

provided for two-way service within the private branch exchange, that is, a private branch exchange subscriber can reach the attendant by way of one of these trunk lines, and the attendant, in turn, can extend a connection to a private branch exchange subscriber over one of the trunk lines.

Referring particularly to the incoming connector shown in Fig. 3, the principal feature shown in connection with this connector consists in relays which are individual to an incoming trunk line from the main exchange, and in combining these relays with the equipment of an incoming connector.

Of this individual equipment, only the polarized relay 327 will be mentioned at this point of the explanation. This relay is normally bridged across the trunk line extending to the main exchange, and, since battery and ground potentials are provided on the distant end of the trunk line, the polarized relay 327 is energized. Accordingly, the polarized relay 327 is shown in operated position, whereas the rest of the equipment of the incoming connector shown in Fig. 3 is shown in normal position.

The detailed explanation of the various types of service provided at the attendant's cabinet will now be presented.

It will be assumed first that a subscriber in the main exchange desires to extend a call to the attendant's position at the private branch exchange.

A connector switch in the main exchange seizes the trunk 200 and 201 leading to the attendant's cabinet, and reverses the battery on the trunk, thereby causing the polarized relay 327 in the incoming connector associated with the trunk to restore. The polarized relay operates armature 328, thereby disconnecting the conductor 302 from the conductor 303 and connecting the conductor 302 to ground over armature 320 and its resting contact. Following the conductor 302 to Fig. 2, it will be seen that a circuit is closed for the busy lamp 302' and that ground is also extended to the conductor 204 which is the private normal conductor of the central office trunk accessible to a local connector in the private branch exchange. By grounding the conductor 204 in the local connector, a seizure of the central office trunk by a private branch exchange subscriber is prevented.

The connector in the central exchange places generator current on the trunk conductors 200 and 201 in order to signal the attendant at the private branch exchange. The signalling current traverses the lower winding of relay 324 in the incoming connector over the following circuit: Conductor 200, springs 213 and 214 of key 208, conductor 305, resting contact controlled by armature 314, condenser 362, lower winding of relay 324, which is in parallel with an impedance 380, resting contact and armature

322, resting contact controlled by armature 316, conductor 306, springs 215 and 216 of key 208, and back to the central main exchange over conductor 201. The relay 324 operates and closes at its armature 326 a holding circuit for itself over its upper winding to ground by way of armature 321 and its resting contact. At armature 325, the relay 324 grounds the conductor 301, thereby connecting a circuit for the answering lamp 301' at the attendant's position.

The attendant, noticing the glowing of the lamp 301', operates the key 223 in order to answer the call. This operation of the key 223 connects the operator's telephone circuit 245 across the central office trunk by way of springs 228 and 229, and the springs 230 and 231. At springs 232 and 233 of the key 223, the impulsive circuit is prepared for the operation of the incoming connector over the impulse conductor 307; at spring 233' and 234, a circuit is closed for the relay 287 which extends from battery, winding of relay 287, resting contact and armature 284, closed impulse contacts of the calling device 246, release key 247, springs 234, spring 233', to ground over armature 285 and its resting contact. Relay 287 operates and closes its armature 288, thereby completing a circuit for the slow acting relay 289. The latter relay operates armature 290 closing thereby another point in the impulsive circuit to the incoming connector.

At springs 224 and 225 of key 223, a circuit is closed over conductor 303 for the relay 318 in the incoming connector. This relay operates, and at its armature 322, removes the polarized relay 327 and the relay 324 from the trunk conductors, and connects the relay 329 across the trunk conductors by way of armature 332 of relay 331. This bridging of the relay 329 across the trunk conductors 200 and 201 provides a loop circuit for the operation of the usual ring-cut-off relay in the central office connector, which operates and removes the generator current from the trunk conductors. At armature 321, the relay 318 opens the locking circuit for the relay 324, allowing the relay 324 to restore, and to remove at its armature 325 ground from the conductor 301, which extinguishes the lamp 301'. At its armature 319, the conductors 302 and 303 are united, and ground is therefore maintained on conductor 302 from the springs 224 and 225 and the conductor 303 in Fig. 2.

Relay 329 operates from current supplied by the connector in the central main exchange, and closes, at its armature 328' a circuit by way of conductor 300 for the operation of the supervisory lamp 300'.

The holding key 220 is now operated, which closes a guarding circuit to relay 318 over conductor 303 so that relay 318 will remain operated when the key 223 at the attendant's position is restored.

The attendant obtains the name or number of the party desired in the private branch exchange and proceeds to set up a connection to that party's line through the incoming connector shown in Fig. 3.

5 Relay 287 of the common relay equipment in the attendant's cabinet, is, as will be remembered, in a series circuit with the impulse contacts of the calling device 246. Accordingly, when the calling device is operated, the relay 287 follows the impulses of each series from the calling device, and, at each deenergization grounds the impulse conductor 307 as follows:

15 Ground at armature 288 and its break contact, make contact and armature 290, springs 233 and 232, conductor 307, springs 335 and 334 of the off-normal contact, winding of the series relay 340, and winding of the vertical magnet 342 to battery. When the connector steps the shaft vertically by one step, the off-normal spring 333 is operated, opening the impulsing circuits over springs 335 and 334 and substituting therefor the circuit including the spring 336. Relay 340 which is a slow acting relay is energized and has operated its armature 341. The remaining impulses of the series are therefore transmitted over the spring 336 of the off-normal contact and over 25 armature 341 and its make contact. Relay 289 in the common relay equipment in the attendant's cabinet remains operated throughout the transmission of impulses on account of being a slow acting relay.

30 Relay 340 deenergizes shortly after the termination of the impulse series and transfers the impulsing circuit to the rotary magnet 358. The rotary magnet is operated by the second series of impulses transmitted from the attendant's calling device 246, in series with the winding of relay 343, armature 356 and its resting contact, armature 349 and its break contact, and winding of the rotary magnet to battery. Relay 343 energizes in 35 series with the rotary magnet and operates armature 345, short circuiting thereby the armature 349 in order to prevent a premature opening of the impulsing circuit when the relay 347 energizes as the private wiper 360 advances over busy lines. At armature 344, the relay 343 connects the relay 347 to the private wiper of the incoming connector.

35 It will be assumed first that the desired line is busy. If this is the case, the private wiper 360 encounters ground at the private bank contact of the called line, and relay 347 operates. At armature 348, it prepares a locking circuit for itself which will be completed by the deenergized relay 343 shortly after the 40 termination of the impulse transmission. At armature 349, the relay 347 opens the circuit to the rotary magnet, which, at the deenergization of relay 343 will also be opened at armature 345. At armature 350, the relay 347 closes a circuit for the transmission of a

busy tone to the trunk conductor 306. The busy tone is transmitted over a conductor 351 which terminates in a tone machine. Thus the attendant is informed that the desired line is busy, and will inform the waiting main 70 exchange subscriber.

Assuming now that the desired line is idle, the private wiper 360 does not encounter ground. Accordingly, the relay 347 does not energize. Shortly after the termination of the impulse transmission, relay 343 deenergizes and moves its armature 344 into the position shown. This operation connects the lower winding of the switching relay 352 to the private wiper 360, and completes the circuit for the operation of the switching relay 352, from ground on conductor 302, armature 348 and its resting contact, lower winding of the switching relay 352, resting contact and armature 344, private wiper 360, 80 and battery over a bridge cut-off relay of the desired subscriber's line equipment. The switching relay operates and closes a locking circuit over its upper winding at its armature 355. At armature 354, direct ground from conductor 302 is connected to the private wiper 360 in order to busy the line. At armature 356, the circuit for the rotary magnet 358 is opened; and at armatures 353 and 357 the connection to the wanted party is 85 completed.

The attendant will now operate the ringing key 235 shown in Fig. 2. This completes a circuit for the relay 295 in the common relay equipment in the attendant's cabinet in 90 series with the relay 312 at the incoming connector.

95 It will be seen that the conductors 309 and 311 are connected together over an impedance 286 at contacts controlled by armatures 284 and 285, respectively, of relay 283. Following the conductors 309 and 311, it will be seen, that these conductors are now connected across the incoming trunk conductors 200 and 201 at armatures 316 and 314 and their make contacts, relay 312 being in operated position. Therefore, the calling section of the trunk line is separated in the connector from the called section, and the call is held over the impedance 286. Relay 312 in 100 the incoming connector has also operated its armatures 315 and 317, and has thereby connected the conductors 308 and 310 to the section of the connection which leads to the called party in the private branch exchange. At armature 313, the relay 312 has substituted a ground circuit on conductor 300 for the circuit which was provided by armature 328' of relay 329.

105 Since the relay 295 in the common relay equipment operates in series with the relay 312 in the incoming connector when the attendant throws the ringing key 235, it will be apparent that ringing current is transmitted to the called substation over the fol- 110 115 120 125 130

lowing circuits: Current source 298, armature 296 and its make contact, conductor 308, armature 317 and its make contact, armature 322 and its make contact, armature 357 5 and its make contact, wiper 361, bell at the called substation, wiper 359 of the incoming connector, make contact and armature 353, armature 315 and its make contact, conductor 310, make contact and armature 297 to ground.

10 The key 235 is not held in the ringing position but thrown at intervals to ring the called station.

15 When the called party in the private branch exchange answers the call, relays 312 and 295 being in position of rest, the circuits for relay 331 in the incoming connector is closed from battery at the central office trunk line through the loop at the called station.

20 Relay 331 operates and opens the circuit to relay 329 at its armature 332. Accordingly, armature 328' of relay 329 removes ground from the conductor 300 and the supervisory lamp 300' is extinguished, indicating to the

25 attendant that the call has been answered. The connection between the calling main exchange party and the private branch exchange subscriber is now completed. The branch exchange subscriber receives talking battery over the trunk line from the central main exchange.

30 The called party at the private branch exchange restores the receiver to the switchhook when the conversation is completed, 35 and opens thereby the locking circuit including the relay 331 in the incoming connector. Accordingly, relay 331 deenergizes, closing the circuit to relay 329. Relay 329 operates over the loop provided by the inter-office trunk and, at armature 328' grounds the conductor 300 to light the supervisory lamp 300'. This serves as disconnect supervision for the attendant.

35 The attendant releases the holding key 220. 40 Ground being removed from conductors 303 and 302, the busy lamp 302' at the attendant's position will be extinguished; ground is also removed from the private normal conductor 204 terminating in a bank contact of a local connector switch. The interoffice trunk is 45 therefore available for service from the private branch exchange to the main exchange. Relay 318 in the incoming connector releases and closes at its armature 321 a circuit for the release magnet 339 from ground, resting contact and armature 321, off-normal springs 338 and 337, winding of the release magnet 339 to battery. At armature 322 the relay 50 55 60 65 318 reconnects the relay 324 and the polarized relay 327 across the trunk conductors. The polarized relay operates because the battery of the central office trunk is now supplied through the lineswitch at the distant end in the central main exchange. The non-inductive resistance 380 in parallel with the lower

winding of relay 324 prevents discharge current from operating relay 324 when connected to the trunk.

70 The operations described in the foregoing in connection with release take place if the main exchange party has also retired from the connection, that is, if the connector in the central exchange has released the interoffice trunk. In this case battery and ground potentials are supplied to the trunk conductors from the lineswitch at the distant exchange end of the trunk line. Should the calling party at the main exchange be still on the line, the connector keeps battery and ground reversed on the trunk conductor, and, upon the release of the equipment as described, the polarized relay in the incoming connector, will remain at normal to hold the central office trunk busy to the attendant and to hold the incoming connector operated until the calling party disconnects. When the calling party replaces the receiver the connector will disconnect from the interoffice trunk and the battery supply of the trunk conductors will be reversed causing the polarized relay in the incoming connector to operate and to make the central office trunk available for outgoing service as described.

75 80 85 90 95 100 105 110 115 120 125 130 The local connectors, such as the one shown in Fig. 1, have access to the central office trunk over the outgoing level. When a connector in the private branch exchange seizes the central office trunk it grounds the conductor 204 causing the lamp 302' to glow, and closing the circuit to relay 318 in the incoming connector. Relay 318 operates, locks to ground on conductor 302, and removes the relay 324 and the polarized relay 327 from the trunk, clearing the trunk of attachments.

110 115 120 125 130 The local connectors in the private branch exchange have also access to the attendant's cabinet over trunks designated 250 and 266 shown in Fig. 2. When a calling subscriber in the private branch exchange operates a connector such as the one shown in Fig. 1, into connection with one of these trunks, say with trunk designated 250, the conductor 253 will be grounded, and a circuit will thereby be completed by way of the springs 255 and 254 to lamp 249. This serves as a signal for the attendant notifying her that a call has been extended by a private branch exchange subscriber. The attendant operates the associated trunk key, in the assumed case the key 248, thereby connecting her telephone circuit 245 across the trunk 250. This circuit may be traced from conductor 251, springs 272 and 273 of key 248, release key 247 and impulse springs of the calling device 246 in series, springs 261 and 260 of key 248, switchhook, receiver and transmitter in series, springs 257 and 256, and conductor 252 to the calling branch exchange subscriber.

5 The attendant obtains the name or number of the party desired, and restores the trunk key 248. She then proceeds to set up the connection to the desired party over a central office trunk. The private branch exchange subscriber requesting the call disconnects and waits until he is called by the attendant.

10 The attendant operates the key 223 associated with the central office trunk, thereby connecting her telephone circuit across the trunk conductors and closing the circuits to relay 318 in the connector in a manner already described. Relay 318 in the incoming connector operates and causes the busy lamp 302' to glow by grounding conductor 302 at armature 319. Ground, it will be remembered is at this time also on conductor 204 which marks the central office trunk busy to other calling connectors in the private branch exchange. Relays 324 and 327 are removed from across the trunk conductors, and the loop circuit to the main exchange is closed by way of relay 329 in the incoming connector. The attendant next operates the key 336, transferring thereby the loop circuit across the central office trunk from relay 329 in the incoming connector to her dialling circuit.

30 Upon operating the key 336, a circuit is closed for the operation of the relay 283 in the common relay equipment at the attendant's position in series with the relay 312 in the incoming connector which may be traced from ground, winding of relay 283, springs 238 and 237, springs 227 and 226, conductor 304, and winding of relay 312 to battery.

40 The operation of the two relays 283 and 312 responsive to the actuation of key 336 effects the transfer of the loop circuit of the inter-office trunk from relay 329 to the dialling equipment of the operator which may be traced as follows: Conductor 200, springs 213 and 214, conductor 305, make contact and armature 314, conductor 311, make contact and armature 285, springs 233' and 234, release key 247, impulse springs 246, armature 284 and its make contact, conductor 309, armature 316 and its make contact, conductor 306, springs 215 and 216, and trunk conductor 201 back to the central exchange.

55 The operator at the private branch exchange now dials the number of the party desired, actuating thereby the switches in the central office to set up connection to the line of the wanted party. The key 336 is restored after the required digits have been transmitted to the central office switches, and, upon restoring the key, the operator's telephone circuit is again connected across the central office trunk, and the trunk loop, which, during dialling extended over the calling device 246 is again transferred to the loop including relay 329 of the incoming connector. Relay 329 therefore operates and connects ground to

conductor 300 in order to light the supervisory lamp 300'.

60 The reconnection of the loop including the relay 329 in substitution of the loop including the impulse device 246 at the attendant's position was brought about by the restoration of the key 336, which, at the contact springs 237 and 238 disconnected the circuit of relay 283 and 312. When relay 283 de-energizes it closes a circuit for relay 287 from ground at its armature 285 by way of springs 233' and 234, and over the impulse device 246, in order to prepare the impulsing circuits for the incoming connector shown in Fig. 3.

70 If the desired party in the main exchange answers, the attendant at the private branch exchange will proceed to set up the connection to the private branch exchange subscriber who requested the call. This connection will be set up over the incoming connector as follows:

75 The attendant operates her calling device 246 in accordance with the digits designating the private branch exchange subscriber's line. The impulses produced by the calling device 246 deenergize the relay 287 a number of times in rapid succession, and this relay, at its armature 288 transmits impulses to the incoming connector by way of the impulse conductor 307 in a manner already described in detail 80 in a previous section of this specification. The incoming connector is thus operated into connection with the line of the private branch exchange subscriber who requested the call.

85 The key 220 at the attendant's position is next operated in order to hold the connection, and the key 235 is operated in order to transmit ringing current to the private branch exchange subscriber. The ringing operation which follows the actuation of the ringing key 235 has already been described in detail and shall not be repeated. While ringing current is placed on the line, the connection to the party in the central office is held through the impedance 286 at the attendant's 90 position in the usual manner.

95 When the private branch exchange subscriber answers the call he completes the loop circuit over the central office trunk, which circuit includes the relay 331. This relay operates and opens at its armature 332 the circuit of the relay 329. Relay 329 releases and opens the circuits to the supervisory lamp 300' which indicates to the attendant that the branch exchange subscriber has answered. The connection is now held by the subscriber who requested the call by way of both trunk conductors and the relay 331 in the incoming connector.

100 Relay 331, in the incoming connector restores when the party who requested the call replaces his receiver, and, in restoring, connects the relay 329 across the central office trunk to maintain a loop for holding the connection in the central office. Relay 329 op- 115

erates and causes the supervisory lamp 300' to glow in order to notify the attendant that the private branch exchange party has retired from the call.

- 5 The attendant then releases the connection by operating the holding key 220 into normal position. This removes ground from the conductor 303 and from the conductor 302. The busy lamp 302' is thereby extinguished; 70
10 ground is removed from the private normal conductor 204 terminating in the multiple of the local connector switches; making the central office trunk available for outgoing service; and opens the circuit of relay 318 in 75
15 the incoming connector. Relay 318 restores and removes relay 329 from across the central office trunk causing the connection in the central office to release.

The attendant, as was previously intimated, has access to the local connectors over the trunks such as 250 and 266 terminating in keys 248 and 264 respectively. When the attendant desires to establish connection with a private branch exchange subscriber, 20 she operates a trunk key such as 248 for example, connecting her telephone circuit 245 across the trunk conductors 251 and 252, which causes a finder switch, such as the one shown at F in Fig. 1, to find this trunk 250 25 and to extend it to a local connector such as the one shown at C in Fig. 1. The attendant dials the number of the party desired, causing the local connector to set up a connection. The dialling circuit extends in this case 30 from the trunk conductor 251, springs 272 and 273, release key 247, impulse contacts of 35 the calling device 246, springs 261 and 260, switchhook of the operator's telephone circuit 245, contact 245', which is operated by the dial 246, springs 257 and 256, and back to 40 the local connector over the trunk conductor 252.

Should the trunk 266 be taken in service instead of trunk 250, the dialling circuits may 45 be traced from conductor 268, springs 272 and 273, springs 258 and 257, contacts 245', switchhook of the operator's telephone circuit, springs 260 and 259, springs 276 and 277, impulse springs 246, release key 247, 50 springs 279 and 278, back to the local connector over the trunk conductor 267.

It will be apparent from the above explanation that the dialling circuit employed by the attendant at the private branch exchange 55 differs with the service rendered. When a call is extended to a private branch exchange subscriber by taking into use one of the trunks 250 or 266, the dialling circuit involves a loop circuit with the impulse contacts of the calling device 246 directly bridged across the dialling conductors. The same is the case when the attendant at the private branch exchange desires to extend a connection to a subscriber in the central main exchange. However, when the operator at the branch 60

exchange extends a call to a branch exchange subscriber by way of the incoming connector shown in Fig. 3, which is the case when a central main exchange subscriber calls the attendant and requests the connection to a branch exchange subscriber, the dialling circuit will involve the interrupter relays 287 and 289 which are controlled by the attendant by means of the calling device 246. 70

The conductors 205, 206 and 207 are, as has already been intimated, reserved for providing night service. When the night key 208 is in operated position, the night telephone connected to the conductors 205, 206 and 207 is directly connected with the central office 75 trunk. The central office trunk is made busy to other connectors in the private branch exchange at springs 209 and 210 of the key 208 80 which connects ground to the private normal conductor 204 terminating in bank contacts at local connectors. The number of night telephones required govern the number of central office trunks used for night service. 85

The purpose of the release key 247 will be explained next. It will be remembered that the release key 247 is, in every case where the calling device 246 is used, connected in series with the impulse contacts. Should the attendant desire to release a partly established connection, she will stop operating the calling device 246 and will open the release key 247. This of course opens the loop circuit to the switch in question and that switch releases. This provision is necessary since it 90 may happen that the operator discovers during the operation of the impulse device 246 that she has dialled the wrong number. In order to forestall wrong connections she has means in the key 247 to release an incompletely 95 called. 100

At 280 is shown a buzzer which may be connected to an armature 292 of relay 291 by means of a key 281. This provision is mostly used in night service or under similar conditions, for example, when the attendant is also charged with various other duties auxiliary to her duty of attending to the switchboard. If this is the case, the key 281 is in operated position and at spring 282 the buzzer is connected to the armature 292 of relay 291. Now, should a call come in, regardless whether the call is from the central exchange or from a subscriber in the private branch exchange, the relay 291 will in any case be operated and will operate its armature 292 thereby closing a circuit for the buzzer 110 115 120 125 130 280.

Having described the equipment in detail, it will be seen, that the invention discloses a very efficient and relatively simple arrangement useful for private branch exchanges. It will be understood that modifications are possible without departing from the spirit of the invention, and it will therefore be appreciated that it is not desired 125 130

to use the invention precisely as shown in the accompanying drawings but to apply its features in accordance with the scope of the appended claims.

What is claimed is:

6. 1. In a telephone system, a main exchange, a private branch exchange provided with an attendant's position, a two conductor trunk line interconnecting said exchanges and terminating at said position, a calling device, means at said position for connecting said calling device directly across said trunk line for directively extending a call to a substation in said main exchange, an automatic switch in said branch exchange, an impulse repeater, means for connecting said calling device and said repeater to said switch, and means in said switch controlled by said repeater in response to its actuation by said calling device for operating said automatic switch to extend a connection to a substation in said branch exchange. 70
10. 2. In a telephone system, a main exchange, a private branch exchange provided with an attendant's position, a two-conductor trunk line interconnecting said exchanges and terminating at said position, a calling device, means at said position for connecting said calling device directly across said trunk line for directively extending a call to a substation in said main exchange, an automatic switch in said branch exchange, an impulse repeater, means for connecting said calling device and said repeater to said switch, means 75 in said switch controlled by said repeater in response to the actuation of said calling device for operating said automatic switch to extend a connection to a substation in said branch exchange, and means at said position 80 for uniting said substations in a conversational circuit. 85
15. 3. In a telephone system, substations, an operator's position, switches accessible to said substations and to said position for extending calls, a calling device at said position, means at said position for seizing one of said switches and for directly connecting said calling device to said seized switch for directively extending a connection to a substation, other switches accessible only to said position, a repeater, means for connecting said calling device to said repeater, and means controlled by said repeater responsive to the actuation of said calling device for operating one of said other switches to extend a call to a substation. 90
20. 4. In a telephone system, substations, an operator's position, switches accessible to said substations and to said position for extending calls, a calling device at said position, means at said position for seizing one of said switches and for directly connecting said calling device to said seized switch for directively extending a connection to a substation, other switches accessible only to said 95 position, an impulse producing device comprising a plurality of relays, means for seizing one of said other switches and associating said impulse producing device therewith, and means for controlling said switch by means of said impulse device to extend a connection to a substation. 100
25. 5. In a telephone system, substations, an operator's position, switches accessible to said substations and to said position for extending calls, a calling device at said position, means at said position for seizing one of said switches and for directly connecting said calling device to said seized switch for directively extending a connection to a substation, other switches accessible only to said position, means for seizing one of said other switches, a repeater, said second means for connecting said calling device and said repeater to said seized other switch, and means in said seized other switch controlled by said repeater responsive to the actuation of said calling device for operating said seized other switch to extend a connection to a substation. 105
30. 6. In a telephone system, a private branch exchange, a distant main exchange, a plurality of two-conductor trunk lines interconnecting said exchanges, each trunk line terminating in the branch exchange in an automatic connector switch, an attendant operator's position at said branch exchange having means for manipulating said trunk lines, a plurality of relays at said position provided for the common use of all trunk lines and associated connectors, and a plurality of relays 110 provided in each of said connectors and serving exclusively the trunk line associated therewith. 115
35. 7. In a telephone system, a private branch exchange, a distant main exchange, a plurality of two-conductor trunk lines interconnecting said exchanges, each trunk line terminating in the branch exchange in an automatic connector switch, an attendant operator's position at said branch exchange having means for manipulating said trunk lines, a plurality of relays at said position including impulse repeating relays and a ringing relay for the common use of all trunk lines and associated connectors, and a plurality of relays 120 provided in each of said connectors and serving exclusively the trunk line connected therewith. 125
40. 8. In a telephone system, a private branch exchange, a distant main exchange, a two-conductor trunk line interconnecting said exchanges and terminating in said branch exchange in an automatic connector switch, an attendant's position at said branch exchange, a manually operable calling device, means for connecting said calling device directly to said trunk line for actuating switches in said main exchange to extend a connection to a certain station thereat, a separate automatically operable impulse 130

transmitter and means for connecting said transmitter to said connector switch for extending a call to a branch exchange station.

9. In a telephone system, a private branch exchange, a distant main exchange, a two-conductor trunk line interconnecting said exchanges and terminating in said branch exchange in an automatic connector switch, an attendant's position at said branch exchange, a manually operable calling device, means for connecting said calling device directly to said trunk line for actuating switches in said main exchange to extend a connection to a certain station thereat, a separate automatically operable impulse transmitter, means for connecting said calling device to said transmitter to control the same, and means for connecting said transmitter to said connector to operate the same to extend a call to a branch exchange station.

10. In a telephone system, a private branch exchange, a distant main exchange, a two-conductor trunk line interconnecting said exchanges and terminating in said branch exchange in an automatic connector switch, an attendant's position at said branch exchange, a manually operable calling device, means for connecting said calling device directly to said trunk line for actuating switches in said main exchange to extend a connection to a certain station thereat, a separate automatically operable impulse transmitter, means for connecting said calling device to said transmitter to control the same, means for connecting said transmitter to said connector to actuate the same to extend a connection to a branch exchange station, and means for uniting said stations in a conversational circuit.

11. In a telephone system, a main exchange, a branch exchange, a plurality of two-way trunks interconnecting said exchanges, each of said trunks terminating in a connector switch in the branch exchange, an operator's position at the branch exchange having access to said trunks, a calling device and a repeater at said position, means for bridging said device directly across one of said trunks for extending calls from the branch exchange to the main exchange, and means for bridging said device and said repeater across a trunk for operating the associated connector switch for extending calls from the main exchange to the branch exchange.

12. In a telephone system, a main exchange, a branch exchange, an operator's position at the branch exchange, a plurality of two-way trunks interconnecting the exchanges and accessible to said position, each trunk terminating in a connector switch in the branch exchange, a plurality of two-way trunks connecting said position with the branch exchange, a calling device and a repeater at said position, means for bridging

said calling device directly across any one of said trunks for extending calls from said position to the exchanges, and means for bridging said device and repeater in series across one of the first mentioned trunks for operating the associated connector switch to extend a call from the main exchange to the branch exchange.

In witness whereof, I hereunto subscribe my name this 22d day of November, A. D. 1927.

ROY FIERO GOULD.
